MUSICAL INSTRUMENT CASE

Marcel O. De Vos, 19922 E. Williams Court,
Grosse Pointe Woods, Mich.

Filed Nov. 18, 1964, Ser. No. 82,682

Term of patent 14 years

(Cl. D87—5)

I claim:

The ornamental design for a musical instrument case, substantially as shown.
